RAILWAY TRAFFIC CONTROLLING
APPARATUS

Howard A. Thompson, Edgewood, and Ralph R. Kemmerer, Swissvale, Pa., assignors to The Union Switch & Signal Company, Swissvale, Pa., a corporation of Pennsylvania

Application January 27, 1938, Serial No. 187,228

19 Claims. (Cl. 246—37)

Our invention relates to railway traffic controlling apparatus of the class wherein coded track circuit energy is utilized to control either or both wayside signals and train-carried cab signals, and more particularly it relates to the application of such apparatus to tracks in either electric or steam propulsion territory over which traffic may move in either direction.

One feature of our invention resides in novel provisions for enabling a single coding device having but one group of contacts to supply the rails of whichever one of two adjoining track sections carries authorized traffic toward the section junction with train-control energy which is coded in accordance with the traffic conditions beyond that junction. Another feature resides in a novel organization of circuits and apparatus which permits each coding device to supply energy to the rails of a plurality of different tracks. A further feature resides in an improved manner of controlling track relays of the centrifugal frequency-selective type in train-control systems of the type above named.

We shall describe several forms of railway traffic controlling apparatus embodying our invention, and shall then point out the novel features thereof in claims.

In the accompanying drawings, Fig. 1 is a diagrammatic representation of a stretch of railway track equipped with two-direction traffic-controlling apparatus embodying our invention.

Fig. 2 is a similar representation of the apparatus of Fig. 1 showing its condition when traffic movements are authorized in the reverse instead of the forward direction. Fig. 3 is a representation of a portion of one of the signal location equipments of the preceding figures showing the apparatus thereof interconnected in a modified manner, and Fig. 4 is a view showing a single code transmitter connected to supply train-control energy to the rails of a plurality of different tracks.

Referring to the drawings, in the several views of which like reference characters designate corresponding parts, the improvements of our invention are there disclosed as being incorporated in a system of controlled manual block signaling for a stretch of track 1—2 over which traffic may move in either direction. In describing the diagrams of these drawings, it will be assumed that the left end thereof is west and the right end east, and that "forward" traffic is eastbound and "reverse" traffic is westbound.

The rails 1 and 2 of the represented track are divided by means of insulated joints 3 into a plu-

rality of successive sections only one of which, F—G, is represented in each of the diagrams of Figs. 1 and 2. The particular stretch of track there shown is intended for use in a railway system employing electric propulsion, and for this reason impedance bonds 4 of the customary form are provided at each pair of insulated joints to conduct propulsion current therearound. It will be apparent, however, that the apparatus of our invention is equally well suited for use on a steam road, in which application the bonds 4 would, of course, be omitted, as in the showings of Figs. 3 and 4.

The rails of each of the referred to sections of track form a part of a track circuit through which train-control energy may be transmitted. Each of these track circuits further includes a pair of track transformers TT and TT' connected with the rails thereof at the east and west ends of the section, respectively, and a track relay TR having a control winding 7 which also is connected with the west ends of the section rails.

A suitable alternating-current source, designated in the diagrams by the terminals B and C, normally supplies, through transformer TT, the track circuit with steady or uninterrupted energy of suitable signal-power frequency, such as 60 or 100 cycles per second. As long as the section is vacant, this energy is transmitted by the rails to the winding 7 to maintain the track relay TR actuated. When, however, a train enters the section, the usual shunting action of its wheels and axles deprives the relay of this steady energy, and thereby initiates control operations which cause coded energy, suitable for controlling train-carried cab signals, to be impressed between the rails.

In the particular arrangement disclosed, this coded energy is supplied to the east end of the track circuit through the transformer TT when the mentioned train is an eastbound one and to the west end of the circuit through the transformer TT' when the traffic to be governed is westbound. In consequence, cab signals carried by a train progressing through the section in either direction are controlled, in the desired manner, by the measure of this rail-transmitted energy which is received from a point ahead of the train by the usual inductive pick-up apparatus mounted on the locomotive front.

Use is made, during operation of the signaling apparatus under conditions of westbound traffic authorization, of an impedance transformer TX and a code-following control relay CR to prevent the pulses of coded energy which the track trans-

former TT¹ at times supplies to the west or relay-connected end of the track circuit from falsely actuating the track relay TR. The primary winding of this transformer is included in the circuit 5 of the track relay control winding 7 in the manner shown, and the secondary winding thereof is arranged to be short-circuited or closed upon itself through a contact 6 of the relay CR at all times except when the transformer TT¹ supplies 10 energy to the track rails. Through circuits later to be described, the relay CR is also energized during each period of such energy supply and caused to bias the named contact upwardly, thereby opening the secondary circuit of the 15 transformer TX upon the occasion of each energy pulse.

With its secondary short-circuited, the transformer TX adds very little to the impedance of the track relay circuit and, under this condition, 20 which is the normal one, the relay TR operates in the same manner as were the transformer not present. When, however, the secondary circuit is opened, the amount of added impedance is increased so substantially as to prevent the track 25 relay from being actuated by the potential which appears between the rails as a result of their energization from the transformer TT¹. In certain cases, moreover, that potential may have an instantaneous polarity which is opposite to 30 that of the current which the winding 7 of relay TR normally receives from the track rails and in those instances it is customary to provide the track relay with means (not shown but one form of which is described in the following paragraph) 35 which make it unresponsive to reverse energization of any degree.

Each of the track relays represented at TR is of the centrifugal frequency-selective type and in addition to the control winding 7 already described as being connected to the rails of the 40 associated track circuit, it is provided with a local winding 8 which is arranged to receive energization from the alternating current source B—C. These two windings form a part of an induction motor which operates the relay contacts by rotating a flyball mechanism 9. As long as 45 this mechanism is at rest, the contacts occupy their downward or unactuated positions. When, however, the device is rotated in a normal or forward direction, the flyballs are moved outwardly by centrifugal action, and this movement is utilized to raise the relay contacts. To prevent the 50 relay from responding to reverse energization of the character referred to in the preceding paragraph, the mechanism 9 is provided with a ratchet device (not shown) which permits the flyballs to be rotated only in the normal or forward (and not in the reverse) direction.

The contacts reach their fully-actuated or front-closed positions only when the speed of this rotation is of the high value which results when the 55 relay windings are energized from the 60 or 100 cycle supply circuit B—C. As any energy of the conventional 25 cycle electric propulsion frequency which may accidentally enter the relay, as under unbalanced track circuit conditions, is incapable of producing the critical speed above referred to, false contact closure, in electrified 60 territory applications, due to stray propulsion current thus becomes impossible.

Coding of the train-control energy supplied at proper times to the trackway through one or the other of the track transformers TT or TT¹ is effected at each of the section-division locations 75 F, G, etc. by a code transmitter CT there in-

stalled in the manner indicated. Each of the transmitters shown by way of illustration is provided with three circuit making-and-breaking contacts 80, 120 and 180 arranged for selective inclusion in the energizing circuit of one or the 5 other of the two transformers just referred to. During operation of the transmitter, these contacts are continuously actuated by a motor or other suitable mechanism (not shown in detail) at three different speeds which for purposes of 10 explanation will be assumed to be such as respectively to provide "slow", "caution" and "proceed" codes of 80, 120 and 180 energy pulses per minute.

Also installed at each section-division location 15 are a pair of relays ET and WT through the medium of which selection is made of the direction in which traffic is authorized to move through the protected stretch of track. When the relays ET at all of the locations are actuated and all of the 20 relays WT are deenergized, the apparatus is set up to authorize and control traffic movements in the eastbound direction. Similarly, when the relays WT at all of the locations are actuated and the relays ET are deenergized, the apparatus is 25 conditioned to authorize and control traffic movements in the westbound direction.

Circuits for controlling these direction-selecting relays are well known, and, since they form no part of the present invention, no attempt has 30 been made to disclose them herein. Typically, however, they may be included in the controlled manual block system previously mentioned and when such is the case, block station operators at opposite ends of the protected stretch of track 35 must first cooperate with each other to obtain the use of the stretch and must then set the relays ET and WT in positions appropriate for the selected direction of traffic movement.

Additionally installed at each of the section 40 division locations is a relay AR which is arranged to connect the associated code transmitter CT with its energizing source B—C and to set up appropriate circuits for distributing the output thereof whenever a train approaches the location 45 from either direction and to maintain the transmitter deenergized and the track transformer TT appropriately energized at all other times. These approach-control relays AR are normally energized from a suitable source of direct current 50 potential, designated in the diagrams by the terminals "plus" and "minus", through control circuits which include track relay contacts 10 and 11, direction-selector relay contacts 12, and location-interconnecting line conductors 13. 55

Further forming a part of the controlled manual block system previously referred to are wayside signals SE positioned adjacent the points of track section division and arranged to control eastbound traffic through the protected stretch 60 and other wayside signals SW similarly located along the trackway and arranged to govern westbound traffic. These signals may be of any suitable form and as here represented are of the semaphore type each capable of showing any one 65 of the indications of "proceed", "caution", "slow" and "stop".

Since the circuits for controlling these wayside signals form no part of the present invention, the details thereof are omitted from the drawings for 70 the sake of simplicity. For present purposes, it is sufficient to state that three relays H, JA and J installed at each section division block are utilized to control the signals through connections which include contacts 14 of each associated di- 75

rection-selector relay WT. When the relays WT are unactuated, as under conditions of eastbound traffic authorization, the named contacts connect the named control relays with the eastbound signals SE and when the relays WT are actuated, as under conditions of westbound traffic authorization, the contacts 14 connect the control relays with the westbound signals SW.

In the particular arrangement represented all of the signals associated with the unauthorized direction of traffic continuously show "stop" and the signals associated with the authorized direction of traffic are controlled in well-known automatic block system manner by the relays H, JA and J. That is, all of these signals not under the control of a train show "proceed" while those at the first, second and third locations immediately behind a train respectively show "stop", "slow" and "caution".

The actuation of the relays H, JA and J which is necessary to effect the named form of signal control may be effected in any suitable manner through well-known control circuits (not shown) which, typically, may include contacts of the track and direction-selecting relays and line conductors interconnecting the apparatus of adjacent signal locations. For purposes of explanation, it will be assumed that relay J is a polarized device and that the just-referred to circuits control it and the relays H and JA in the following manner.

When all sections of the protected stretch of track are unoccupied, all three of the relays are actuated, the polar contacts of relay J now being in the "normal" position. In the event that one of the sections becomes occupied by a train, all three of the relays at the traffic entering end thereof become deenergized and hence unactuated. At the next signal location to the rear, relay H only is actuated; at the third location behind the train relays J and JA are also actuated, the polar contacts of relay J now being in the "reversed" position; and at succeeding locations to the rear all three relays are actuated, the polar contacts of relay J now occupying their "normal" position.

In the improved arrangement of our invention, contacts 15 and 16, respectively, carried by the signal-control relays H and JA at each section-division location are utilized to select which one of the three codes of 80, 120 and 180 energy pulses per minute is distributed from the associated code transmitter CT. When both of the relays H and JA are actuated, the circuits are set up to transmit the "proceed" or 180 code; when relay H is actuated and relay JA is unactuated the distributing circuits receive the "caution" or 120 code; and when both relays are unactuated, the circuits are set up to transmit the "slow" or 80 code.

Under conditions of eastbound traffic authorization (see Fig. 1), energy of the particular coding thus selected is at proper times transmitted through a contact 18 of the approach control relay AR to the track transformer TT and also to the local winding 8 of the track relay TR at the signal location to the rear or west of the supplying code transmitter CT. The track transformer circuit then includes contacts 19 and 20 of the relays AR and ET and the track relay coding circuit then includes contacts 21 and 22 of relays AR and ET, a line conductor 23 which interconnects adjacent signal locations, and a contact 24 of relay ET at the westward or rear location.

Under conditions of westbound traffic authorization (see Fig. 2), energy of the selected coding is distributed at proper times from each code transmitter CT to the winding of the code following relay CR through a circuit which includes the previously referred to contact 18 of relay AR and a contact 26 of relay WT. Through a contact 28, the thus actuated relay CR supplies coded energy to the track transformer TT and to the local winding 8 of the associated track relay TR. The circuit for effecting the latter supply includes a contact 29 of the relay WT.

The various component parts of our improved signaling apparatus having been described, attention will now be directed to the manner of operation of the complete system shown in the diagram of Figs. 1 and 2. As this operation is somewhat different when the traffic to be governed is westbound than when it is eastbound, separate explanation will be given for traffic movements in each of these two directions.

Attention will first be directed to what takes place when the direction of authorized traffic movement is eastbound, as indicated by the diagram of Fig. 1. In this case all of the eastbound selector relays ET are actuated and all of the westbound relays WT are deenergized. This causes all of the westbound signals SW to show "stop" and the eastbound signals SE to be controlled in automatic block system manner.

When all of the protected blocks are unoccupied, the control winding 7 of each track relay TR receives steady energy from the rails of the associated or forward track section, and the local winding 8 of that relay also receives steady energy from a circuit which extends from supply terminal B at the next location to the east through front-closed contact 21 of relay AR at that advance location, conductor 33, front-closed contact 22 of relay ET at the same advance location, line conductor 23, front-closed contact 24 of relay ET at the associated location, conductor 31 and the winding 8 of relay TR back to the supply terminal C.

This causes all of the track relays to maintain their contacts in the front-closed positions. In consequence, all of the approach relays AR also receive energizing current through circuits which, in each case, may be traced as follows: from a positive supply terminal at the next location to the west, through front-closed contact 11 of relay TR at that rearward location, line conductor 13, back-closed contact 12 of relay WT at the associated location, conductor 32, and the winding of the relay AR back to a negative supply terminal. As a result, these relays AR all hold their contacts in the upward or front-closed positions.

Under the named condition, the rails of the track section immediately behind or west of each signal location are supplied with steady energy through the track transformer TT. The track transformer energizing circuit may in each case be traced from a supply terminal B at the associated location through front-closed contact 19 of relay AR, conductor 33, front-closed contact 20 of relay ET, conductor 34 and the primary winding of the transformer back to supply terminal C.

Under the stated conditions, all of the eastbound wayside signals SE are, in addition, caused, by virtue of relays J, JA and H all being actuated as before described, to give the "clear" or "proceed" indication displayed by device SE.

In the event that an eastbound train VE oc-

copies one of the sections of the protected stretch of track, the wheels and axles thereof shunt the trackway potential from between the rails and deenergize the track relay TR which is connected thereto. This relay drops its contacts to their back positions as shown at location F in Fig. 1, opening, at contact 11, the actuating circuit for the approach relay AR at the next location to the east. That relay now drops its contacts to their back positions, as shown at location G in Fig. 1.

Contact 36 of this approach relay now completes a circuit which places the associated code transmitter CT in operation. This circuit extends from supply terminal B through the contact 36, conductor 31, and the operating winding of the transmitter back to supply terminal C. At the same time, contact 38 of the relay AR connects the coding contacts 80, 120, and 180 of the transmitter with another supply terminal B and contacts 15, 21 and 19 of the relay set up circuits through which energy coded by one of the transmitter contacts is distributed to the local winding 8 of the track relay TR at the next location to the west and to the track transformer TT at the associated location.

The referred to energizing circuit for the transformer TT extends from a supply terminal B through back-closed contact 38 of relay AR, conductor 40, coding contact 180 of the transmitter CT, conductor 41, front-closed contact 16 of relay JA, conductor 42, front-closed contact 15 of relay H, conductor 43, back-closed contact 18 of relay AR, conductor 44, back-closed contact 19 of relay AR, conductor 33, front-closed contact 20 of relay ET, conductor 34, and the primary winding of transformer TT back to supply terminal C. The referred to energizing circuit for the local winding of the track relay TR at the next location to the rear may be traced from supply terminal B through contact 180 of the code transmitter CT at the forward location, conductor 42, back-closed contact 18 of relay AR, conductors 44 and 45, back-closed contact 21 of relay AR, conductor 29, front-closed contact 22 of relay ET, line conductor 23, front-closed contact 24 of relay ET at the rear location, conductor 31, and the winding 8 of the rear-location track relay TR, back to supply terminal C.

Through the transformer TT, the east or traffic-leaving end of the occupied track section is, in the manner described above, supplied with train-control energy of the 180 or "proceed" code. This energy causes current to circulate through the rails ahead of the wheels and axles of the eastbound train VE which current inductively transfers energy, through pick-up devices mounted on the locomotive front, to the train-carried control apparatus and causes the cab signals to show "proceed", thereby indicating that the two track sections immediately ahead are unoccupied.

The rails of the section occupied by the train VE transmit no trackway energy to the rear of the train and the apparatus at the associated rearward signal location assumes the condition represented at F in Fig. 1. There the westbound track transformer TT is deenergized as is also the control winding 1 of the track relay TR. The local winding 8 of this relay receives energy of the 180 code through the circuit previously traced (which circuit includes eastwardly extending line conductor 23), which energy damps or retards any motion of the centrifugal mechanism 9 of the relay and thus hastens the opening of the contacts following the initial entry of the train

into the track section. Approach relay AR holds its contacts in the front-closed position as a result of receiving actuating current through the previously-traced circuit which includes the front-closed contact 11 of the track relay TR at the next location to the west.

The code transmitter CT at the location under discussion accordingly remains unenergized, as represented at F, and the associated track transformer TT supplies steady energy to the rails of the track section to the rear as a result of the primary winding being connected with the source B-C through front-closed contacts 19 and 20 of relays AR and ET. The relays H, JA and J are all unactuated and cause the controlled signal to show the indication of "stop", as displayed by device SEf. The now back-closed contacts 15 and 16 of relays H and JA set up a circuit, of which conductor 47 forms a part, through which the code transmitter CT will supply the track transformer TT with energy of the 80 or "slow" code should a second train enter the section to the immediate rear.

At the second signal location behind the eastbound train VE, the condition of the equipment is as follows: Both the control and local windings of the track relay TR receive steady energy and the relay holds its contacts in their front-closed positions. Approach relay AR is also actuated and the code transmitter CT is unenergized. The rails of the track section to the rear are supplied with steady energy by way of track transformer TT connected with source B-C through contacts 19 and 20 of relays AR and ET. Relay H is actuated and relays J and JA are unactuated thereby causing the controlled signal SE to show "slow" and setting up, by means of contacts 15 and 16, a circuit, including conductor 46, through which the contact 120 of the code transmitter CT will supply the track transformer TT with energy of the 120 or "caution" code should a second train enter the section to the immediate rear.

At the third location behind the eastbound train VE, the equipment has the following condition: Both the track and approach relays TR and AR are actuated. Code transmitter CT is unenergized and track transformer TT supplies steady energy to the rails of the track section to the rear. Relays H, JA and J are actuated (polar relay J reversely), causing the controlled signal to show "caution" and setting up a circuit through which the code transmitter will supply the track transformer TT with energy of the 180 or "proceed" code should a second train enter the section to the immediate rear.

Finally at the fourth and at all succeeding signal locations (which are associated with unoccupied sections) behind the eastbound train VE, the condition of the equipment is as follows: The track and approach relays TR and AR are actuated. Code transmitter CT is deenergized and track transformer TT supplies steady energy to the rails of the track section to the rear. Relays H, JA and J are actuated (polar relay J normally) and cause the controlled signal to show "proceed" and set up a circuit through which the code transmitter will supply the track transformer TT with energy of the 180 or "proceed" code should a second train enter the section to the immediate rear.

Assume now that while the first eastbound train VE continues to occupy the section F-G of Fig. 1, a second eastbound train (not shown) does approach from the rear. As this second

train approaches the third, second and first track sections behind the first train, it will respectively receive from signals SE the usual visual indications of "proceed", "caution" and "slow", and train-carried signals in the cab of its locomotive will be caused to show corresponding indications as the train advances into the successive sections named. This comes about in the following manner.

10 In entering each section, the second train de-energizes the associated track relay TR thereby also deenergizing the approach relay AR at the signal location immediately ahead. This places in operation the code transmitter CT at that 15 advance location and causes the associated track transformer TT to supply coded train control energy to the forward end of the section. For the third and succeeding sections behind the first train, this energy is, as has been seen, of the 180 or "proceed" code and for the second and first sections behind the one occupied by the first train, it is respectively of the 120 or "caution" code and the 80 or "slow" code.

As an eastbound train moves out of each track section, the following operations take place. The removal of the interconnection of the rails of the section allows these rails to transmit coded energy to the control winding 7 of the track relay TR at the west end of the section and the local winding 8 of this relay continues to receive energy of the same coding through a circuit which includes line conductor 23. This energization imparts rotation to the fly-ball mechanism 9 of the relay and within the space of only one or two code pulses brings it up to full speed. Since both of the windings 7 and 8 are energized and deenergized simultaneously, the rotor 9 freely drifts during the "off" code periods and is free from the damping action which would be present were one of the windings to remain energized continuously.

The resulting front closure of the track relay contacts reestablishes, at contact 11, the energizing circuit for the approach relay AR at the next location east. That relay now actuates its contacts to their upward positions to effect the following actions: Contacts 36 and 38 shut down the code transmitter CT at the forward location; contact 19 connects the associated track transformer TT with its source of steady energization B-C; and contact 21 reestablishes the circuit, of which line conductor 23 forms a part, through which steady energization is supplied to the local winding 8 of the track relay TR at the rear location. The mentioned track transformer TT now supplies steady energy to the associated track rails and thereby maintains the track relay at the rear location in its normally actuated condition.

All portions of the train-control apparatus are now restored to the unoccupied-track-section condition. The operations described above, which are incident to such restoration, proceed with great rapidity, the total time required therefor typically being of the order of only a second or two.

Operating conditions for eastbound traffic having been described, attention will now be given to the manner in which the improved train-control apparatus of our invention operates when the direction of authorized traffic movement is west, as represented by the diagram of Fig. 2. In this case, all of the westbound direction selector relays WT are actuated and all of the eastbound relays SE are unenergized, thereby causing all of the eastbound signals SE to show "stop"

and the westbound signals SW to be controlled in automatic-block-system manner.

When all of the protected blocks are unoccupied, the condition of the control equipment at each of the signal locations is as follows: The track relay TR maintains its contacts in the front-closed positions as a result of its control winding 7 receiving steady energy from the rails of the associated or eastward track circuit and of the local winding 8 also receiving steady energy. The local-winding supply circuit now extends from supply terminal B, through back-closed contact 28 of relay CR, conductor 48, front-closed contact 29 of relay WT, conductor 31, and the relay winding 8 back to terminal C. 10 The approach relay AR also maintains its contacts in the upwardly actuated positions as a result of receiving energizing current through a circuit which extends from a positive supply terminal, through front-closed contact 10 of relay TR, conductor 50, front-closed contact 12 of relay WT, conductor 32 and the relay winding back to a negative terminal. All three of the relays H, JA and J are actuated (polar relay J normally) and each controlled wayside signal SW 15 is thereby caused to give the "clear" or "proceed" indication.

At all times that westbound movement is authorized, the track transformer TT at each location continuously supplies the rails of the track section immediately to the west with steady energy. Under these conditions the transformer energizing circuit extends from supply terminal B, through back-closed contact 20 of relay ET, conductor 34 and the primary winding of the 30 transformer back to terminal C. At no time is this circuit interrupted, in the arrangement shown, as long as the authorized direction of movement continues to be westbound.

In the event that a westbound train VW occupies one of the sections of the protected stretch of track, the wheels and axles thereof shunt the trackway potential from between the rails and deenergize the particular track relay TR which is connected thereto. This relay drops its contacts to their back positions, as shown at F in Fig. 2, and opens, at contact 10, the actuating circuit for the approach relay AR, causing that relay also to drop its contacts to their back positions.

Contacts 36 and 38 of relay AR now complete energizing circuits for the code transmitter CT and contact 18 sets up a circuit through which the transmitter supplies coded energy to the winding of code-following relay CR. This circuit extends from supply terminal B, through back-closed contact 38 of relay AR, conductor 40, coding contact 180 of device CT, conductor 41, front-closed contact 16 of relay JA, conductor 42, front-closed contact 15 of relay H, conductor 43, 45 back-closed contact 18 of relay AR, conductor 51, front-closed contact 26 of relay WT, conductor 52 and the winding of the relay back to terminal C.

Upon each pulse of coded energy thus received, relay CR actuates its contacts to their upward positions and during each period of deenergization which follows allows them to return to their back-closed positions. Contact 28 thus causes the transformer TT to be supplied with correspondingly spaced pulses of energization by periodically completing a circuit which extends from supply terminal B through the contact 28 (in its front-closed position), conductor 53 and the primary winding of the transformer back to a sup-

ply terminal C. This same contact also causes the local winding 8 of the track relay TR to be supplied with similarly coded energy by periodically completing a circuit which extends from supply terminal B, through the contact 28 (in its back-closed position), conductor 48, front-closed contact 29 of relay WT, conductor 31 and the winding 8 back to terminal C.

In the manner described above, the traffic-leaving end of the occupied track section is supplied with train-control energy of the 180 or "proceed" code. Due to the before-explained action of the impedance transformer TX and the contact 6 of relay CR, the track relay TR is prevented from being falsely operated by this energy and remains continuously unactuated as long as the associated track section is occupied. It will also be noted that the interruptions of the energizing circuit for the local winding 8 of the track relay TR which contact 28 of relay CR effects coincide with the pulses of coded train-control energy which are supplied to the trackway through transformer TT1. This further safeguards the track relay against false actuation of the character referred to above. Moreover, in the event that the energy from transformer TT1 is of the reversed relative instantaneous polarity discussed in an earlier portion of this specification, the reverse-rotation-preventing ratchet mechanism (not shown) of relay TR then absolutely prevents response regardless of what the magnitude of that energy may be.

At the first signal location behind or to the east of the westbound train VW, the apparatus assumes the condition represented at G in Fig. 2. There the track relay TR is actuated by steady energy received from the rails of the associated track circuit, the approach relay AR also holds its contacts in their upward positions, the code transmitter CT is not operating, the code-following relay CR is unactuated, and the track transformer TT supplies steady energy to the rails of the occupied section. Contact 28 completes the steady energizing circuit for the local winding of relay TR and interrupts the primary circuit of the track transformer TT1. The relays H, JA and J are all unactuated and cause the controlled signal to show "stop." The back-closed contacts 15 and 16 of relays H and JA now set up a circuit through which the code transmitter CT will supply the relay CR with energy of the 80 or "slow" code should a second train enter the section to the immediate rear.

At the second signal location behind the train VW, the condition of the equipment is as follows: Both the control and local windings of the track relay TR receive steady energy and the relay holds its contacts in their front-closed positions. Approach relay AR is also actuated, the code transmitter CT is unenergized, the code-following relay CR is unactuated, the track transformer TT supplies steady energy to rails of the forward track section, and the primary circuit of the track transformer TT1 is interrupted at contact 28. Relay H is actuated and relays J and JA are unactuated, thereby causing the controlled signal SW to show "slow" and setting up, through contacts 15 and 16, a circuit through which the contact 120 of the code transmitter CT will cause the track transformer TT1 to be supplied with energy of the 120 or "caution" code should a train enter the section to the immediate rear.

At the third location behind the occupied section, the equipment assumes the following condition. Track relay TR is actuated, as is also ap-

proach relay AR; code transmitter CT, relay AR, and track transformer TT1 are unenergized; and the track transformer TT supplies steady energy to the rails of the track section in advance. Relays H, JA and J are actuated (polar relay J reversely) causing the controlled signal to show "caution" and setting up a circuit through which the code transmitter will cause the track transformer TT1 to be supplied with energy of the 180 or "proceed" code should a second train enter the section to the immediate rear.

Finally, at the fourth and at all succeeding signal locations (associated with unoccupied sections) behind the westbound train VW, the condition of the equipment is as follows: The track and approach relays TR and AR are actuated, code transmitter CT, relay AR and track transformer TT1 are unenergized, and the track transformer TT supplies steady energy to the rails of the track section in advance. Relays H, JA and J are actuated (polar relay J normally) and cause the controlled signal to show "proceed" and set up a circuit through which the code transmitter will cause the track transformer TT1 to be supplied with energy of the 180 or "proceed" code should a second train enter the section to the immediate rear.

Assume now that while the first westbound train VW continues to occupy the section G-F of Fig. 2, a second westbound train (not shown) does approach from the rear. As this second train approaches the third, second and first track sections behind the first train it will respectively receive from the signals SW the usual visual indications of "proceed", "caution" and "slow" and signals in its cab will be caused to show corresponding indications as the train advances into the successive sections named. This comes about in the following manner.

In entering each section, the second train de-energizes the associated track relay TR, thereby also deenergizing the approach relay AR at the same location. This places in operation the associated code transmitter CT and causes the track transformer TT1 to supply coded train-control energy to the forward end of the entered section. For the third and succeeding sections behind the first train, this energy is of the 180 or "proceed" code and for the second and first sections behind the one occupied by the first train it is respectively of the 120 or "caution" and the 80 or "slow" codes.

As a westbound train moves out of each track section the following operations take place. The removal of the interconnection of the rails of this section allows these rails to transmit steady energy from the track transformer TT at the east end of the section to the control winding 7 of the track relay TR at the west end. The local winding 8 of this relay continues to receive energy coded by the contact 28 of relay AR and the pulses of this coded energy coincide with the periods of low impedance for the circuit through which the control winding 7 receives steady trackway energy. In consequence, rotation is imparted to the fly-ball mechanism 9 of the track relay TR and within the space of a very small number of code cycles the mechanism attains full speed.

The resulting front closure of the track relay contact reestablishes, at contact 10, the energizing circuit for the relay AR. In actuating its contacts to their upward positions that relay shuts down the code transmitter CT and interrupts the energizing circuit for the winding of relay CR. Track transformer TT1 is now deenergized and

track transformer TT at the west end of the section continues to supply steady energy over the rails to the control winding of the track relay TR. The local winding of this relay now also receives steady energy through the back-closed contact 28 of relay CR and, in all other respects, the condition of the equipment is that appropriate for the now unoccupied track section.

The above described operations incident to the restoration of the apparatus associated with each track section to normal or "vacant" condition upon the departure of a westbound train from the section take place very rapidly so that, as in the case of eastbound restoration, the total time required typically is of the order of but one or two seconds only.

Referring now to Fig. 3, we have there represented the westbound track transformer TT1 as being interconnected with the associated apparatus at each of the section-division locations in a manner which causes it to receive coded energy directly from the code transmitter CT instead of through the auxiliary circuit shown in Figs. 1 and 2 as including conductor 53 and the contact 28 of the code-following relay CR. In the arrangement shown in Fig. 3, the primary winding of the transformer is, through conductor 53, directly connected with the conductor 52 through which the code transmitter supplies energy to the actuating winding of the relay CR. Contact 28 of this relay now supplies coded energy only to the local winding of the track relay TR through conductor 48.

Operation of the apparatus when thus connected is essentially the same as that already explained for the equipment of Figs. 1 and 2. Each pulse of coded energy from the transmitter CT now simultaneously energizes the transformer TT1 and the relay CR and the periods of deenergization of both of these devices are also simultaneous. When a westbound train vacates the associated section of track the apparatus restores itself to the unoccupied operating condition in exactly the same manner as that previously described.

It has been seen that the improved apparatus of our invention includes novel provisions whereby each code transmitter CT supplies, from but a single group of contacts 80-120-180, coded train-control energy to either of two track transformers TT and TT1, respectively, connected with opposing ends of track circuits which include the rails of adjoining sections of a two-direction running track 1-2. This is a feature of great practical advantage in that it eliminates the need at each section-division location for duplicate transmitters or for duplicate sets of synchronously operated contacts in a single coding device.

In applications wherein a plurality of parallel tracks are involved, these advantages may be even further extended, as shown in Fig. 4. In that figure, we have illustrated one manner in which each of the code transmitters CT may be arranged to supply coded train-control energy to equipment associated with more than one two-direction running railway track. By way of illustration of this plural application, two tracks respectively consisting of rails 1 and 2 and rails O1 and O2 have been represented.

Associated with each of these tracks at each point of section-division 3 is train-governing equipment (only partially reproduced in Fig. 4) of the character shown in the preceding figures. In the arrangement of Fig. 4, a single coding device CT supplies its coded energy to distributing

conductors 55, 56 and 57 which transmit it to the code selecting circuits (which include contacts 15 and 16 of the relays H and JA) of corresponding equipment for each of the several different tracks. Through similarly arranged control conductors 59 and 60, the contacts 36 and 38 of the approach relay AR included in the equipment associated with each and every one of the tracks may initiate and maintain operation of the transmitter CT.

Such operation, of course, makes coded energy available to all of the selecting circuits just referred to as including relay contacts 15 and 16. Unless, however, such energy is actually needed, as evidenced by an unactuating condition of the approach relay AR, the distributing circuit (which includes conductor 43) remains open at contact 18 and the energy is not transmitted to the train control apparatus. It will thus be seen that in the improved arrangement of our invention the number of tracks which can be supplied from a single code transmitter is limited only by the capacity of the coding contacts thereof.

While we have described our invention as being incorporated in apparatus which supplies only three train governing codes to the trackway and which forms a part of a controlled manual block system, it will be understood that our improved equipment may readily be adapted to other applications wherein provision is made for either more or less than three different train-governing indications.

Likewise, while we have restricted our disclosure to train-control systems employing track relays of a particular frequency-selective form especially suited for connection to electric propulsion tracks, it will be apparent that the broad improvements of our invention are equally applicable to train-control systems employing track relays of other types.

Although we have herein shown and described only a few forms of railway traffic controlling apparatus embodying our invention, it is understood that various changes and modifications may be made therein within the scope of the appended claims without departing from the spirit and scope of our invention.

Having thus described our invention, what we claim is:

1. In combination, a section of railway track, a track relay provided with a control winding connected to the track rails at one end of said section and with a local winding, means for supplying steady alternating-current energy to said rails at the opposite end of the section at all times and to said local winding when the section is vacant, and a coding device rendered effective by said track relay when a train occupies the section and adapted at such times to supply coded alternating-current energy to said local winding and to the track rails at the relay-connected end of the section.

2. In combination, a section of railway track, a track relay provided with a control winding connected to the track rails at one end of said section and with a local winding, means for supplying steady alternating-current energy to said rails at the opposite end of the section at all times and to said local winding when the section is vacant, a coding device rendered effective by said track relay when a train occupies the section and adapted at such times to supply coded energy to the track rails at the relay-connected end of the section and to said local wind-

ing, and means for increasing the impedance of the control winding circuit of the track relay during each pulse of said coded energy.

3. In combination, a section of railway track, 5 a track relay provided with a control winding connected to the track rails at the traffic-leaving end of said section and with a local winding, circuits for continuously supplying steady energy to said rails at the traffic-entering end 10 of the section and to said local winding, a coding device, means rendered effective by said track relay for placing said coding device in operation when a train occupies the section, and means responsive to said operation for supplying coded 15 train-control energy to said rails at the traffic-leaving end of the section and for interrupting the energizing circuit for the local winding of the track relay during each pulse of said energy.
4. In combination, a section of railway track, 20 a track relay provided with a control winding connected to the track rails at the traffic-leaving end of said section and with a local winding, circuits for continuously supplying steady energy to said rails at the traffic-entering end of the 25 section and to said local winding, a coding device, means rendered effective by said track relay for placing said coding device in operation when a train occupies the section and causing it to supply coded train-control energy to said 30 rails at the traffic-leaving end of the section, and a code-following relay energized by said coding device and adapted to increase the impedance of the control-winding circuit of the track relay and to interrupt the energizing circuit for 35 the track relay local winding during each pulse of said train-control energy.
5. In combination, a section of railway track, a track transformer connected to the rails thereof at the traffic-entering end of the section and 40 arranged continuously to supply steady energy thereto, a second track transformer connected with said rails at the traffic-leaving end of the section, a track relay provided with a control winding also connected to said rails at the traffic-leaving end of the section and with a local winding, a coding device, an approach relay controlled by said track relay and adapted to connect said local winding with a source of steady energy when the section is vacant and to place 45 said coding device in operation when a train occupies the section, and a code-following relay energized from said coding device and adapted at such times to cause coded train-control energy to be supplied to said second-named track transformer, to increase the impedance of the control winding circuit of the track relay during each pulse of said energy and to interrupt the energizing circuit for the local winding of the track relay during each of said pulses.
6. In combination, a section of railway track, 50 a coding device, a track relay having a control winding connected with the rails of said section and a local winding, an approach relay controlled by said track relay, means including said approach relay for causing said coding device to supply coded train-control energy to said rails when a train occupies the section, a code-following relay controlled by said coding device, and means including said code-following relay 55 for supplying coded energy to the local winding of said track relay and for increasing the impedance of the control winding circuit of the track relay in step with the pulses of said coded energy.
7. In combination, a section of railway track, 60 75 a track relay provided with a control winding

connected to the rails of said section and with a local winding, means effective when the section is vacant for supplying steady alternating-current energy to said local winding and to said rails, and a coding device rendered effective by 5 said track relay when a train occupies the section and adapted at such times to supply coded alternating current energy to said local winding and to said rails at the traffic-leaving end of the section.

8. In combination, a section of railway track, a track relay provided with a control winding connected to the rails of said section at the traffic-entering end thereof and with a local winding, circuits for supplying steady energy to said 15 rails at the traffic-leaving end of the section and to said local winding, a coding device, and an approach relay controlled by said track relay and adapted to include said coding device in said rail and local winding supply circuits when 20 a train occupies the section.

9. In combination, a section of railway track, a track relay provided with a control winding connected to the track rails at the traffic-entering end of the section and with a local winding, 25 circuits for supplying steady energy to said local winding and to the section rails at the traffic-leaving end of the section, a coding device, and an approach relay controlled by said track relay and adapted to place said coding device in operation 30 and include it in said local winding and rail supply circuits when a train occupies the section.

10. In combination, a section of railway track, a track transformer connected to the rails thereof at the traffic-leaving end of said section, a 35 track relay provided with a control winding connected to the track rails at the traffic-entering end of said section and with a local winding, a coding device, and an approach relay controlled by said track relay and adapted to connect said 40 track transformer and said local winding with a source of steady alternating-current energy when the section is vacant and to place said coding device in operation and include it in the energizing circuits of said transformer and of said local 45 winding when a train occupies the section.

11. In combination, a stretch of railway track divided into a plurality of sections, a track relay located at each point of junction of adjacent sections and connected near that point with the 50 rails of the particular one of the there-adjoining sections which is on a given side of said point, each of said track relays being adapted to respond to the entry of a train into the section with which the relay is connected, a coding device also 55 installed at each of said points of track section division and having but a single group of coding contacts, means for causing each of said coding devices to be rendered operative by the track relay at the location of the device when a train 60 approaches that location from the said side of the relay-connected section and to be rendered operative by the track relay which is connected with the remote end of the other there-adjoining section when a train approaches the location 65 from the opposing side of that other section, and means including the said coding-device contacts for supplying train-control energy to the device-location end of whichever of said two there-adjoining sections is between the location and the 70 approaching traffic and over which said traffic must pass in reaching the location of said device.

12. In combination, a stretch of railway track divided into a plurality of sections, a coding device located at each point of junction of adjacent 75

sections and having a single group of contacts adapted to code trackway energy at one or another of a plurality of different rates, a track relay also installed at each of said points of track 5 section division connected near that point with the rails of the particular one of the there-adjoining sections which is on a given side of said point, each of said track relays being adapted to respond to the entry of a train into the section 10 with which the relay is connected, direction-selecting means for causing each of said coding devices selectively to be rendered operative by the track relay at the same own location or by the track relay at the remote end of the opposing track 15 section, a plurality of signal-control relays operatively associated with each of said track relays and actuated in accordance with traffic conditions in advance of their location, and means governed by said signal-control relays and including the contacts of the coding device at each 20 location for supplying energy of one or another of said different codes to the rails of the particular one of the two location-adjoining track sections which is between the location and the approaching traffic and over which said traffic must pass in reaching said location.

13. In combination, a plurality of railway tracks each of which includes a pair of successive sections which adjoin at approximately the same 0 location along the right-of-way, traffic-governing equipment associated with each pair of the said parallel adjoining sections of said different tracks, a single code-transmitter installed at the said common location of track section junction 5 and having but a single group of coding contacts, and means including said contacts for supplying coded energy to the rails of any one of the said parallel adjoining sections of any one of the said tracks.

14. In combination, a plurality of railway tracks each of which includes a pair of successive sections which adjoin at approximately the same location along the right-of-way, traffic-governing equipment associated with each pair of the said parallel adjoining sections of said different tracks, a single code-transmitter installed at the said common location of track section junction and having an operating mechanism and but a single group of contacts, means including said contacts for supplying coded energy to the rails of any one of the said parallel adjoining sections of any one of the said tracks, and means forming a part of each of said traffic-governing equipments for controlling the operating mechanism of said transmitter.

15. In combination, a section of railway track through which traffic may move either in a normal direction or in a reversed direction, a first circuit by way of which the rails of said section may be supplied with energy at the end thereof which marks the exit for normal direction traffic, a second circuit by way of which said rails may be supplied with energy at the end of the section which marks the exit for reversed direction traffic, first and second coding devices respectively located at said first-circuit and said second-circuit ends of the section, first and second approach relays for respectively governing the operation of said first and second coding devices, a track relay connected to receive energy from said rails at one of said section ends, means effective under all unoccupied conditions of the section for connecting one of said rail supply circuits with a source of uncoded energy thereby to maintain said track relay picked up whenever the

section is vacant, direction-selector relays for determining whether authorized traffic through the section shall be in said normal direction or in said reversed direction, means including said selector relays for causing said track relay to control said first approach relay when traffic in said normal direction is authorized and to control said second approach relay when traffic in said reversed direction is authorized, means effective under said conditions of normal direction authorization and including said first approach relay for placing said first coding device in operation upon a release of said track relay and for causing said first circuit then to supply said rails with energy which is coded by that device, and means effective under said conditions of reversed direction authorization and including said second approach relay for placing said second coding device in operation upon a release of said track relay and for causing said second circuit then to supply said rails with energy which is coded by that device.

16. In combination, a section of railway track through which traffic may move either in a normal direction or in a reversed direction, a first circuit by way of which the rails of said section may be supplied with energy at the end thereof which marks the exit for normal direction traffic, a second circuit by way of which said rails may be supplied with energy at the end of the section which marks the exit for reversed direction traffic, first and second coding devices respectively located at said first-circuit and said second-circuit ends of the section, first and second approach relays for respectively governing the operation of said first and second coding devices, a track relay connected to receive energy from said rails at one of said section ends, means effective under all unoccupied conditions of the section for connecting one of said rail supply circuits with a source of uncoded energy thereby to maintain said track relay picked up whenever the section is vacant, direction-selector relays for determining whether authorized traffic through the section shall be in said normal direction or in said reversed direction, means including said selector relays for causing said track relay to control said first approach relay when traffic in said normal direction is authorized and to control said second approach relay when traffic in said reversed direction is authorized, means effective under said conditions of normal direction authorization and including said first approach relay for placing said first coding device in operation upon a release of said track relay and for causing said first circuit then to supply said rails with energy which is coded by that device, means effective under said conditions of reversed direction authorization and including said second approach relay for placing said second coding device in operation upon a release of said track relay and for causing said second circuit then to supply said rails with energy which is coded by that device, and means for increasing the impedance of the said connection of said track relay with said rails during each pulse of the coded energy with which said rails are supplied at the section end where said track relay connection is made.

17. In combination, adjoining first and second sections of railway track over which traffic may move either in a normal direction or in a reversed direction, a coding device installed at the point of junction of said two sections and having but

a single group of contacts, an approach relay for governing the operation of said device, a first circuit through which energy may be supplied to the rails of said first section at the end thereof which adjoins the second section, a second circuit through which energy may be supplied to the rails of said second section at the end thereof which adjoins the first section, a first track relay connected to receive energy from the rails of said first section and adapted to release whenever that section becomes occupied, a second track relay connected to receive energy from the rails of said second section and adapted to release whenever that section becomes occupied, direction-selector relays for determining whether authorized traffic through the sections shall be in said normal direction or in said reversed direction, means including said selector relays for causing said first track relay to control said approach relay when traffic in said normal direction is authorized and for causing said second track relay to control said approach relay when traffic in said reversed direction is authorized, means effective under said conditions of normal direction authorization and including said approach relay for placing said coding device in operation upon a release of said first track relay and for causing said first circuit then to supply said first-section rails with energy which is coded by the said contacts of said device, and means effective under said conditions of reversed direction authorization and also including said approach relay for placing said coding device in operation upon a release of said second track relay and for causing said second circuit then to supply said second-section rails with energy which is coded by the said contacts of said device, and having but a single group of contacts, an approach relay for governing the operation of said device, a first circuit through which energy may be supplied to the rails of said first section at the end thereof which adjoins the second section, a second circuit through which energy may be supplied to the rails of said second section at the end thereof which adjoins the first section, a first track relay connected to receive energy from the rails of said first section and adapted to release whenever that section becomes occupied, a second track relay connected to receive energy from the rails of said second section at the end thereof which adjoins the first section, a first track relay connected to receive energy from the rails of said first section and adapted to release whenever that section becomes occupied, direction-selector relays for determining whether authorized traffic through the sections shall be in said normal direction or in said reversed direction, means including said selector relays for causing said first track relay to control said approach relay when traffic in said normal

direction is authorized and for causing said second track relay to control said approach relay when traffic in said reversed direction is authorized, means effective under said conditions of normal direction authorization and including said approach relay for placing said coding device in operation upon a release of said first track relay and for causing said first circuit then to supply said first-section rails with energy which is coded by the said contacts of said device, means effective under said conditions of reversed direction authorization and also including said approach relay for placing said coding device in operation upon a release of said second track relay and for causing said second circuit then to supply said second-section rails with energy which is coded by the said contacts of said device, and a code following relay effective upon supply of energy through said second circuit to said second section to increase the impedance of the rail connecting circuit for the associated track relay during each pulse of said energy. 5 10 15 20

19. In combination, adjoining first and second sections of railway track over which traffic may move in either direction, a first wayside signal at the point of junction of said sections for governing traffic moves in one direction, a second wayside signal at the same location for governing traffic moves in the opposite direction, a code transmitter also installed at said junction point and having but a single group of contacts, an approach relay for governing the operation of said transmitter, traffic responsive relays for governing the operation of one or the other of said wayside signals and for determining which of the contacts of said transmitter group is to be the active coding member, first and second circuits through which energy may respectively be supplied to the rails of said first and second track sections, a first track relay responsive to the entry of a train into said first section, a second track relay responsive to the entry of a train into said second section, direction-selector relays for establishing the direction that traffic is authorized to move through said sections, means including said approach relay for selecting the wayside signal that said traffic responsive relays are to govern and for setting up a connection of said active-determined coding contact with the rail supply circuit for the particular one of said two sections over which traffic in the authorized direction must approach the point of section junction, and means including said direction-selector relays and said approach relay and effective upon a release of the track relay which is associated with said established section of traffic approach to cause a completion of the aforesaid set up connection and a placement in operation of said code transmitter contacts whereby the rails of said section of traffic approach will receive coded energy which is suitable for controlling train carried cab signals. 25 30 35 40 45 50 55 60

HOWARD A. THOMPSON.

CERTIFICATE OF CORRECTION.

Patent No. 2,175,722.

October 10, 1939.

HOWARD A. THOMPSON, ET AL.

It is hereby certified that error appears in the printed specification of the above numbered patent requiring correction as follows: Page 9, first column, line 13, claim 12, for the words "the same own" read at the same; and that the said Letters Patent should be read with this correction therein that the same may conform to the record of the case in the Patent Office.

Signed and sealed this 7th day of November, A. D. 1939.

(Seal)

Henry Van Arsdale,
Acting Commissioner of Patents.
